UNITED STATES PATENT OFFICE

158,949

OUTDOOR FIREPLACE

Lester T. Ferrin, Tonasket, Wash.

Application July 16, 1949, Serial No. 3,947

Term of patent 14 years

(Cl. D81—10)

To all whom it may concern:

Be it known that I, Lester T. Ferrin, a citizen of the United States, residing at Tonasket, in Okanogan County and State of Washington, have invented a new, original, and ornamental Design for an Outdoor Fireplace, of which the following is a specification, reference being had to the accompanying drawing, forming a part thereof.

Fig. 1 is a perspective view showing the front and one side of an outdoor fireplace embodying my new design; and

Fig. 2 is a perspective view on an enlarged scale showing the top, front and the same side shown in Fig. 1.

The side not shown is substantially like the side shown.

I claim:

The ornamental design for an outdoor fireplace, as shown and described.

LESTER T. FERRIN.
